Patented July 4, 1967

208,028

CLOTHES RACK OR SIMILAR ARTICLE

Albert Spielman, 43 Grand St.,
Brooklyn, N.Y. 11211

Filed Jan. 26, 1966, Ser. No. 776

Term of patent 14 years

(Cl. D33—3)

Fig. 1

Fig. 2

Fig. 3

Fig. 4

Fig. 5

Fig. 6

FIGURE 1 is a side elevational view of a clothes rack or similar article, showing my new design;

I claim:

The ornamental design for a clothes rack or similar article, substantially as shown.
